DESIGN FOR A TOY SEEDER

Edmund W. Baggott, Brooklyn, N. Y., assignor to Ideal Novelty & Toy Co., Hollis, N. Y., a corporation of New York

Application August 24, 1948, Serial No. 148,267

Term of patent 7 years

(Cl. D34—15)

To all whom it may concern:

Be it known that I, Edmund W. Baggott, a citizen of the United States of America, residing at Brooklyn, in the county of Kings and State of New York, have invented a new, original, and ornamental Design for a Toy Seeder, of which the following is a specification, reference being had to the accompanying drawing, forming part thereof.

In the drawing:

Fig. 1 is a side elevational view of a toy seeder, showing my new design;

Fig. 2 is a top plan view thereof, and

Fig. 3 is a rear elevational view.

I claim:

The ornamental design for a toy seeder, substantially as shown.

EDMUND W. BAGGOTT.
